UNITED STATES PATENT OFFICE

SAMUEL COHEN, OF BROOKLYN, NEW YORK

AMPLIFICATION SYSTEM

Application filed September 8, 1924. Serial No. 736,602.

My invention relates broadly to amplification of electrical energy by electron tube circuits and more particularly to a system of amplification where a plurality of tubes in an amplifier may be operated without interference due to the setting up of undesired oscillatory currents within the amplifier circuits.

One of the objects of my invention is to provide an amplification system of high stability operating to increase the amplitude of incoming signaling energy but not being influenced by local oscillation or regeneration within the amplifier circuits.

Another object of my invention is to provide means for connection in various types of electron tube amplification circuits for stabilizing the circuits, enabling the efficient operation of the system at the signaling frequency without the generation of oscillations within the circuits by reason of the inherent capacity coupling between tube electrodes which normally causes feed back and regeneration, the interfering currents being transferred from one electron tube circuit to another by reason of the resonance which exists between the several stages of the apparatus.

Still another object of my invention is to provide a shunt circuit arrangement related to each tube for preventing the spilling over of the tube into a condition of regeneration by reason of self-excitation, thereby securing true repeater action throughout a plurality of tubes.

A further object of my invention is to provide a circuit arrangement including resistance and capacity in shunt with the tube electrodes functioning to shift the phase of interfering currents in the amplifying system to a value so different from the phase of the received signaling currents that the tendency of the tube to oscillate or regenerate is nullified.

My invention further resides in the provision of a phase displacement circuit for undesired oscillatory currents for connection in a variety of different electron tube amplifying systems, whereby the characteristics of the interfering currents are so altered with respect to the characteristics of the signal-

ing currents that the tubes will cease oscillating or regenerating and operate as true repeaters.

My invention will be more clearly understood from the following specification by reference to the accompanying drawings, in which:

Figures 1 and 2 are theoretical diagrams illustrating the principle of my invention; Fig. 3 shows an application of my invention to a tuned radio frequency amplifier circuit used in conjunction with an electron tube detector in a radio receiving receiving system; and Fig. 4 is a wiring diagram illustrating a modified arrangement of the phase displacement circuits in connection with the coupling inductances of a tuned radio frequency amplifier circuit operating in conjunction with an electron tube detector at a radio receiver.

Heretofore in the art amplifying systems have embodied certain difficulties causing unstable operation. This has been particularly true in circuits employing tuned radio frequency amplification where multi-stage amplifiers are used. One of the main causes of trouble is the inherent capacity coupling between tube electrodes, causing feed back and regeneration, a condition which exists when resonance between circuits occur at each stage in the system.

Several methods have been evolved for counteracting or neutralizing this difficulty. One method is the utilization of a third electro-motive force for counteracting the disturbing E. M. F. This disturbing E. M. F. is usually derived from the grid and plate circuits of the amplifier by means of an electromagnetic coupling between the grid and plate circuits. An E. M. F. is thus derived, whose magnitude, and phase is equal and opposite to the disturbing E. M. F. The difficulty of this method is the necessity of varying or changing the coupling for different operating frequencies for the adjustment is very critical. Another method heretofore proposed is to balance the electrostatic capacity of the tube. In this method the usual Wheatstone bridge arrangement is used wherein small balancing capacities are arranged in the circuit in such manner as to balance out the

troublesome capacity coupling in the circuit.

My invention employs a radically different principle than any of the methods heretofore proposed. By means of the circuit arrangement described herein a practically perfect amplifier working as a true repeater without utilizing regeneration in obtaining maximum amplification is secured. The disturbing E. M. F. is completely destroyed by changing its phase relation with respect to the other existing electro-motive forces comprising the signaling currents. The disturbances existing in radio frequency amplifier valves is due to the mutual capacity of the electrodes; namely, the capacity between grid and filament, filament and plate and plate and grid. If the circuits in which the tube electrodes are connected are caused to be in resonance with each other, the mutual capacity coupling between the grid and plate is sufficient to set the tube in an oscillating state. This may also be explained due to the fact that the field of the grid-plate condenser reacts on the grid filament condenser so as to produce a voltage in this condenser in phase with the impressed E. M. F. This produces negative conductance in the input circuit, thus inducting a transfer of power from the plate to the grid circuit with no other coupling between the grid and plate other than the existence of the mutual capacity coupling between the grid and plate.

An analytical analysis of the phenomena that takes place in an electron tube and particularly the part that plays the important rôle of causing the disturbances due to the mutual capacity may be considered from Fig. 1 of the drawings. In this diagram G, P, and F correspond to the grid, plate and filament of an electron tube respectively. The capacity C_1 corresponds to the electrostatic capacity between grid and filament electrodes; C_2 the electrostatic capacity between the plate and filament electrodes and C_3 the mutual electrostatic capacity of grid to plate. The impressed voltage e_1 may be derived from the secondary s of a coupling transformer having an inductance L_1 . The corresponding symbols for the remainder of the circuit are:

r_g = input grid resistance

i_g = grid current

μe_g = alternating plate voltage where μ is the amplifying constant of the tube.

r_p = plate resistance

r_o = load resistance

L_o = load inductance

The voltage of the grid will depend upon the input resistance and this resistance is a function of the load inductance, plate resistance, grid capacity and the mutual capacity C_3 . The input effective resistance may be expressed as

$$r_o = -\frac{L_o C_3}{r_p (C_1 C_3)^2}$$

It can be shown that for pure inductance in

the output circuit, that is when ($r_o = 0$) that the input resistance r_g becomes negative which is a condition for self oscillation. The vector angle between the load inductance and the load resistance is

$$\varphi = \tan^{-1} \frac{L_o}{r_o}$$

It can be shown that as the angle φ decreases, the negative value of r_g decreases and finally becomes positive. It is apparent therefore that if the phase angle is caused to approach a value where the input resistance is such as to prevent the tube from oscillating and at the same time permit the tube to operate as a true repeater, then and only then will the system in question perform the duties required. I accomplish the displacement of the phase angle of the undesired currents with respect to the signaling currents by the arrangement shown in Figure 2 where resistance R_4 and condenser C_4 are shunted across the mutual capacity C_3 between the grid and plate electrodes. The tendency of the tube to oscillate depends upon the mutual capacity C_3 and the phase relation of the currents in the input and output circuits. The phase angle of the currents in the input and output circuits between the plate and grid electrodes being altered by reason of the change of the effective coupling capacity C_3 , the tube will cease oscillating or regenerating. The shunt resistance R_4 and the condenser C_4 are also arranged to prevent the grid from becoming positive and places a negative bias on the grid. Experience has shown that C_4 has a value greater than C_3 and exceeds C_3 by a value approximately $C_3 \times 10^3$. The phase relation of the shunting network with respect to the coupling capacity C_3 may be represented by the following equation:

$$\varphi = \tan^{-1} \frac{b_o}{g_o}$$

where φ = phase angle

b_o = total susceptance

g_o = conductance

The proper constants can be computed for the determination of the shunt resistance and the capacitance for the proper phase angle in order that the tube made function as a true radio frequency repeater without falling into the condition of oscillation. The function of the resistance is therefore to change the phase angle of the coupling current with respect to its voltage, to cause the absorption of the feed back power of the plate circuit to the grid circuit as rapidly as it is generated and to enable the grid to be negatively biased by energy derived from the plate circuit. The application of this principle to electron tube repeating amplifiers is therefore apparent since the drawback with radio frequency amplifiers, particularly for frequencies greater than 10^6 , is the tendency to regeneration and

sustained oscillation; a condition of instability. This condition arises when resonance of the circuits is approached to the incoming carrier frequency.

5 The theoretical principles illustrated in Figs. 1 and 2 are shown in Fig. 3 as applied to a tuned radio frequency amplification system wherein reference character 1 designates a receiving antenna system with ground connection 2 including in circuit therewith the primary winding 3 of coupling transformer 4. The secondary winding 5 of transformer 4 is connected to the input circuit of the first stage of radio frequency amplification including electron tube 6. Electron tube 6 is shown containing filament electrode 7, grid electrode 8 and plate electrode 9. The input circuit of tube 6 includes secondary winding 5 tuned by condenser 10. The output circuit of tube 6 includes primary inductance 11 of coupling transformer 16 connected to bus 12 and thence to the source of B battery potential represented at 15. Filament electrode 7 is energized from battery 15. Secondary winding 17 of coupling transformer 16 is tuned by condenser 18 and connects to the input circuit or across the grid and filament electrodes of electron tube 19 forming the second stage of radio frequency amplification in the amplifying system. The output circuit connected across the plate and filament electrodes contains primary winding 20 of coupling transformer 21 and source of B battery potential 14. The secondary winding 22 of the coupling transformer 21 is tuned by variable condenser 23 and connects to the input circuit or across the grid and filament electrodes of tube 24 forming the third stage of radio frequency amplification in the amplifying system. The output circuit of tube 24 across the plate and filament electrodes thereof includes primary winding 25 of coupling transformer 26 connected through bus 12 with B battery 14. The secondary winding 27 of coupling transformer 26 is tuned by variable condenser 28 and connects to the input circuit of the detector tube 29 including grid condenser and grid leak 30 in the grid circuit thereof and the responsive device 31 in the output circuit thereof connected to a tap 32 on B battery 14. A by-pass condenser 33 of relatively high capacity is connected across the filament and plate battery 14 and 15 of the amplifying system. The plate and grid electrodes of each of the tubes is shunted by the phase displacement circuit R_4 and C_4 as previously illustrated in Fig. 2. This circuit is so related to the input and output circuits of the tubes as to bias the grid electrode 60 negatively at the same time that the circuit operates in conjunction with the inherent capacity existing between the grid and plate electrodes for shifting the phase of the interfering currents with respect to the phase of the signaling currents thereby destroying any

tendency of the disturbing currents to interfere with the signaling currents.

As heretofore stated, by properly adjusting this shunt circuit, the tube of each stage is prevented from spilling over and regenerating at the same time that a negative potential is placed on the grid. From actual practice as obtained from tests, the value of the capacity C_4 should be approximately 200 times as great as the grid plate capacity of the tube. The resistance R_4 was found to vary from 25,000 to 50,000 ohms. The proper value of resistance has to be determined by trial depending upon the tube characteristics and the tube impedance. However, once found it becomes fixed. The entire circuit remains stable in operation independent of the frequency and setting of each respective amplifier circuit. On account of the true repeater action obtainable in this system, without the usual oscillations and regeneration obtained with other systems of radio frequency amplification, it becomes possible to utilize step-up voltage transformation in the coupling transformers 4, 16, 21 and 26. Transformation ratio of 6:1 between primary and secondary winding have been used with success. The electromagnetic coupling between primary and secondary windings must be rigid, that is a tight and close coupling must be employed. The distributed capacity of the primary winding must be exceeding small and its resistance must be kept down to a minimum. It is important that the electromagnetic and electrostatic coupling between each transformer be kept at a minimum. To accomplish this it was found necessary to mount each transformer so that their planes are at right angles to each other. At times it was found necessary to shield each transformer in order to reduce the electromagnetic stray field of each transformer and it was found that the physical dimensions of the windings had to be kept small, all of these factors operating to decrease the effects of capacity coupling between the tube electrodes.

It is apparent that in such a system as herein described that tuning of each stage is necessary in order to obtain maximum sensitivity and minimum interference. However, the difficulty of adjusting a number of controls may be overcome by tuning the entire system by either one or two controls by mechanically coupling all the tuning condensers of each stage and adjusting the circuit by means of a single knob. The antenna coupling transformer 4 should be tuned independently of the radio frequency transformers 16, 21, and 26. The sensitivity and selectivity of the set is thus preserved while the number of tuning controls is reduced to a minimum.

In order to further increase the selectivity and better the stability of the amplifying system I may employ the circuit arrangement illustrated in Fig. 4 where the phase displace-

ment circuits also include a portion of the inductance of the input and output circuits. I have represented the phase displacement circuit C_4 and R_4 in the first stage of radio frequency amplification in shunt with the input and output circuits of tube 6 including a portion 35 of secondary inductance 5 and a portion 36 of primary inductance 11. The phase displacement circuit for tube 19 has been represented as including capacities C_4 and resistance R_4 and portions 37 and 38 of secondary coupling coil 17 and primary coupling coil 20 respectively. As indicated at 39 the resistance R_4 may be made variable 15 for controlling the phase of the shunt circuit.

The circuit arrangements shown are to be considered in the illustrative sense rather than in the limiting sense. I may apply the principle of my invention to a variety of electron tube circuits. The invention is particularly adaptable to reflex circuits for in this type of double duty circuit it is very difficult to prevent the tubes from falling into oscillation. I have successfully applied my invention to a reflex set including three stages of tuned radio frequency amplification, crystal detector, and two stages of audio frequency amplification with very stable operation without indication of oscillations or regeneration. With the resistance R_4 constructed so that as to be readily varied perfect control of the stability of amplifier circuits is obtainable with tubes having different characteristics and it becomes possible to adjust each circuit to a highly sensitive condition whereby high amplification is obtained. I desire that it be understood that the principle of my invention may be applied to various amplification circuits, as for example, the intermediate amplifier circuit of a superheterodyne receiving system or to power amplifiers in transmitting circuits and that I intend no limitations upon the invention other than are imposed by the scope of the appended claims.

What I claim and desire to secure by Letters Patent of the United States is as follows:

50. 1. An amplification system comprising in combination a plurality of electron tubes, each having grid, filament and plate electrodes, input and output circuits interlinking the electrodes of one of said electron tubes with the electrodes of a succeeding electron tube, inductances in each of said circuits, and a circuit including a resistance and condenser operative independently of frequency changes in said tube circuits connected between points intermediate the ends of each of said inductances in the path of interfering currents for displacing the phase of interfering currents with respect to the phase of signaling currents in said system.
55. 2. An amplification system comprising in

combination a plurality of electron tubes, each having grid, filament and plate electrodes, input and output circuits interlinking the electrodes of one of said electron tubes with the electrodes of a succeeding electron tube, inductances in each of said circuits and means comprising a capacity and resistance operative independently of frequency changes in said tube circuits connected between points intermediate the ends of each of said inductances in the path of interfering currents and operating to displace the phase of interfering currents with respect to the phase of signaling currents in said amplification system.

3. An amplification system comprising in combination a plurality of electron tubes, each having grid, filament and plate electrodes having inherent capacity coupling therebetween, input and output circuits interconnecting the electrodes of one of said electron tubes with the electrodes of a succeeding electron tube, inductances in each of said circuits and a circuit electrically related to the inherent capacity coupling of said electrodes operative independently of frequency changes in said tube circuits and connected between points intermediate the ends of said inductances in the path of interfering currents for displacing the phase of interfering currents with respect to the phase of signaling currents in said amplification system.
